(57) **CLAIM**

The ornamental design for a medical lamp, as shown and described.

DESCRIPTION

FIG. 1 is a perspective view of my design;
FIG. 2 is a front view of the design of FIG. 1;
FIG. 3 is a rear view of the design of FIG. 1;
FIG. 4 is a right side view of the design of FIG. 1;
FIG. 5 is a left side view of the design of FIG. 1;
FIG. 6 is a top view of the design of FIG. 1;
FIG. 7 is a bottom view of the design of FIG. 1;
FIG. 8 is a perspective view of another design;
FIG. 9 is a front view of the design of FIG. 8;
FIG. 10 is a rear view of the design of FIG. 8;
FIG. 11 is a right side view of the design of FIG. 8;
FIG. 12 is a left side view of the design of FIG. 8;
FIG. 13 is a top view of the design of FIG. 8;
FIG. 14 is a bottom view of the design of FIG. 8;
FIG. 15 is a perspective view of yet another design;
FIG. 16 is a front view of the design of FIG. 15;
FIG. 17 is a rear view of the design of FIG. 15;
FIG. 18 is a right side view of the design of FIG. 15;
FIG. 19 is a left side view of the design of FIG. 15;
FIG. 20 is a top view of the design of FIG. 15;
FIG. 21 is a bottom view of the design of FIG. 15;
FIG. 22 is a perspective view of yet another design;
FIG. 23 is a front view of the design of FIG. 22;
FIG. 24 is a rear view of the design of FIG. 22;
FIG. 25 is a right side view of the design of FIG. 22;
FIG. 26 is a left side view of the design of FIG. 22;
FIG. 27 is a top view of the design of FIG. 22;
FIG. 28 is a bottom view of the design of FIG. 22;
FIG. 29 is a perspective view of yet another design;
FIG. 30 is a front view of the design of FIG. 29;
FIG. 31 is a rear view of the design of FIG. 29;
FIG. 32 is a right side view of the design of FIG. 29;
FIG. 33 is a left side view of the design of FIG. 29;
FIG. 34 is a top view of the design of FIG. 29; and,
FIG. 35 is a bottom view of the design of FIG. 29.
